CLAIM

We claim the ornamental design for a gas burner set, as
shown and described.

DESCRIPTION

FIGS. 1–8 illustrate a first embodiment of a gas burner set in
which:

FIG. 1 is a perspective view showing the gas burner set on
an example cooktop;

FIG. 2 is a perspective view of the gas burner set;

FIG. 3 is a top view thereof;

FIG. 4 is a bottom view thereof;

FIG. 5 is a front view thereof;

FIG. 6 is a left side view thereof;

FIG. 7 is a rear view thereof; and

FIG. 8 is a right side view thereof.

FIGS. 9–15 illustrate a second embodiment of the gas burner
set in which:

FIG. 9 is a perspective view of the gas burner set;

FIG. 10 is a top view thereof;

FIG. 11 is a bottom view thereof;

FIG. 12 is a front view thereof;

FIG. 13 is a left side view thereof;

FIG. 14 is a rear view thereof; and,

FIG. 15 is a right side view thereof.

Dashed broken lines are used in the drawings to illustrate
environment and portions of the gas burner set that form no
part of the claimed design. Dot-dash lines are used on the
burner set to represent a boundary of the claim and dot-dash
lines are used on the stovetop to represent environment that
is broken away to better visualize features of the design, and
both form no part of the claimed design.
